US0D1103527S

(12) **United States Design Patent** (10) **Patent No.:** **US D1,103,527 S**
(45) **Date of Patent:** **** Nov. 25, 2025**

(54) **DUST BAG CONNECTOR PLATE**

(71) Applicant: **Dongguan Huaying Zhizao Co., Ltd.**,
Dongguan (CN)

(72) Inventor: **Gang Chen**, Neijiang (CN)

(73) Assignee: **Dongguan Huaying Zhizao Co., Ltd.**,
Dongguan (CN)

(**) Term: **15 Years**

(21) Appl. No.: **29/994,573**

(22) Filed: **Mar. 21, 2025**

(51) LOC (15) Cl. **15-05**

(52) U.S. Cl.

USPC **D32/30**

(58) **Field of Classification Search**

USPC D32/15-24, 25, 30, 31; D23/365
CPC A47L 9/1436; A47L 9/1427; A47L 9/149;

A47L 9/14; A47L 9/102

(57) **CLAIM**

The ornamental design for a dust bag connector plate, as shown and described.

DESCRIPTION

FIG. 1 is a front perspective view of a dust bag connector plate, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate portions of the dust bag connector plate, which form no part of the claimed design.

1 Claim, 8 Drawing Sheets
